AUTOMATIC FILTERING PRESS

Fred S. Carver, Short Hills, N. J.

Application April 27, 1937, Serial No. 139,215

1 Claim. (Cl. 100—50)

My invention relates to an automatic filtering press for separating materials containing solids and liquids into such respective components.

It is an object of the invention to provide a press in which pots are eliminated and also the sliding thereof in and out as in previous types, and to substitute a single set of container rings for such pots, which container rings can be filled through an opening or openings in the side walls thereof while remaining within the press, thereby providing a self-contained press which is simple, fast and automatic in its operation.

Another object is to provide for the filling of the container rings through the side walls thereof at points symmetrically located and to thereby form a cake of balanced density.

A further object is to provide filling check valves which can be momentarily locked open so that the inlet passages can be blown out and cleaned.

In the embodiment selected for illustration, the arrangement is as a so-called vertical press and this press will be so described, but other arrangements may be used.

Other objects will appear in connection with the description of the construction and operation of apparatus as shown in the accompanying drawings, in which

Fig. 1 is a side view of a vertical press embodying my invention with the ram down;

Fig. 2 is a front view in part section with the ram down and the containers in extended relation and showing the chambers filled with material to be filtered;

Fig. 3 is a view and section similar to Fig. 2 but with the ram up and the press closed against the pressed cakes consisting of the solid constituents of the material treated;

Fig. 4 is a view and section similar to Figs. 2 and 3, with the ram back in original down position and the container rings retracted, and showing the stripped cakes exposed ready to be removed;

Fig. 5 is a partial section on the line 5—5 of Fig. 2; and

Fig. 6 is a partial section of one of the container rings on the line 6—6 of Fig. 5.

The press frame as shown comprises the base 2 containing hydraulic ram cylinder 4, columns 6, 6, preferably one at each of the four corners, and pressure head 8.

Between pressure head 8 and the hydraulic ram are interposed platens 10, 10, of which four are shown. Platens 10, 10 are guided to travel

axially by the columns 6, 6. For each platen 10 there is a corresponding container ring 12, four thereof being shown in the drawings, but the number of rings and platens can be varied as desired.

The container ring 12 for each platen 10 telescopes about an upwardly extending plunger portion 14 of its platen. On the upper face of the plunger portion 14 of each platen 10 is a filter plate 16 which forms the floor wall of the chamber 12' in the corresponding ring 12. There is also a filter plate 18 on the under side of each of the platens 10, except the bottom one, and such filter plate 18 is adapted to form the ceiling wall of the chamber 12' in the next lower ring 12 when the press is closed. Narrow grooves 19 are provided in platens 10 behind filter plates 18 for lateral exit of fluid expressed through filter plates 18, and similar outlet means may be provided for lateral exit of fluid expressed through filter plates 16.

For each container ring 12 there is a set of preferably four springs 20. Springs 20 are interposed between projecting lugs 22 on the container rings 12 and corresponding projecting lugs 24 on the platens 10.

A series of steps 26 is provided at each side of the press. Each series consists of pairs of steps spaced successively farther apart toward the top of the press. Cross bars 27 are fitted on top of the two topmost sets of steps. In the embodiment shown, there are four platens. When the hydraulic ram piston 25 is retracted, the bottom-most platen rests directly upon the ram piston 25, the platen next above rests on its corresponding set of steps 26, and the two topmost platens rest upon the two pairs of cross bars 27. Thus fixed supports are provided for all of the platens when the ram piston is retracted, while the platens are allowed to move upwardly when the ram piston is extended. Moreover, by virtue of this construction, all of the extending edges of the platens can be made identical with the exception of the lowermost one where the extending edge is omitted.

In the head 8 of the press two hydraulic cylinders 28, 28 are provided. Plungers 30, 30 working in these cylinders actuate rods 32 extending downwardly through openings in the several platens 10 and container rings 12. Said plunger rods 32 are stepped down as indicated at 34, 34, in such manner that the stepped-down parts 34 contact the upper sides of the respective container rings 12, and the lower ends of rods 30 may engage a seat in the lowermost ring 12.

The distances between steps 34, 34 are substantially the same as between steps 26, 26. Bushings 38 may be provided at these contact points if desired, the arrangement and step-spacing being such that the container rings 12 may be actuated by rods 32 to move down against springs 20 when the ram 25 is retracted (Figs. 2 and 4).

Filling means are provided for supplying the material to be pressed to chambers 12' in the rings 12, the inlets 40 for this purpose extending through the side wall of each of rings 12, as for example, the rear wall, as seen in Fig. 2.

This preferably semi-fluid material is delivered under pressure preferably by pumping through inlet valve 41 to inlet pipe 42 to which is connected a vertical pipe 44, this part of the piping being stationary on the press. Swiveled to manifold pipe 44 and to rings 12 respectively are walking pipes 46, 46, with swivel joints 48 between them, said walking pipes 46 leading from supply pipe 44 to inlets 40 into the chambers 12' in the container rings 12.

Feed check valves 50 are provided for each of the inlets 40. Each feed check valve 50 has a spring 52 tending to hold it closed, and stem 54 of valve 50 is provided with a handle 56 having a skirt 57 providing bayonet-joint-like means for temporarily locking the valve 50 in open position to permit blowing through the check valve 50 to clean it out, the open position so provided being indicated in dotted lines in Fig. 6.

Feed pipe 42 is preferably provided with a relief valve 58, referred to below.

The platens 10 are preferably hollow and provided with walking pipes 60, 60 for supplying steam for heating the platens and the material being pressed.

The material to be pressed, such as ground cocoa beans, known as cocoa liquor, for one of many instances, is fed to the press in pumpable condition, being pumped or forced from a supply source through the inlet control valve 41 which is opened for this purpose, and through pipes 42, 44 and 46 and inlet passages 40, past the check valves 50, which have been released to bear against their seats by means of handles 56, into the chambers 12' within the container rings 12. Thus chambers 12' are filled with the semi-liquid material, any air previously in them having escaped through the filter plates 16, 18. Relief valve 58 serves to limit the pressure that can be applied to the supply line to thereby avoid excessive filling pressures and limit the extent to which filtering by pumping can take place before pressing. Relief valve 58 may be dispensed with, however, and effective pressure filter pressing performed by pumping prior to mechanical pressing by means of the hydraulic ram.

The apparatus is shown in Fig. 2 with the chambers 12' in the container rings 12 filled as has just been described. After the chambers 12' are filled, and any desired further pressure filtering has been performed at this stage, valve 41 is closed, though this is not always necessary because of the provision of check valves 50, and hydraulic pressure is admitted to the cylinder 4 at its inlet 62. Ram 25 advancing slowly by hydraulic pressure elevates and foreshortens the telescoping arrangement of platen, plungers and container rings, thereby reducing the height of pressure chambers 12' as the liquid is expressed through filter plates 16 and 18, the parts coming finally to the position shown in Fig. 3, with only cakes of the solids remaining in chambers 12'.

The liquid portion of the material, expressed

through the filter plates 16, 18, flows out through the clearances between the platen plungers 14 and container rings 12, also into the gutters 64 at the top of each container ring 12 and down through passages from gutter to gutter in the different platens, and is finally collected together in the main gutter 66 of the bottom platen, and delivered by exit spout 67 to any suitable collecting means (not shown).

As the ram 25 is advanced, the platens 10 are raised from their initial positions, leaving their step supports 26, 26, and the springs 20, 20 are compressed. Also the ejector plungers 38 are pushed up in their cylinders 28 by elevation of plunger rods 32 actuated by the raising of the lowermost ring 12.

When the pressing is complete, the ram 25 is retracted and the container rings 12, with their respective platens 10, follow the receding ram back under the influence of expanding springs 20 together with the weight of the several parts, the platens finally coming to rest at their initial station positions supported upon their respective step-supports 26, 26. This leaves the cakes 68 in the upper portions of the container rings 10 with some open space below the cakes. The cakes are now ready to be stripped for removal.

Hydraulic pressure is now admitted to the upper ends of the cylinders 28 to force the plungers 38 and connected push rods 32 downwardly.

The container rings 12 are thereby telescoped downwardly over the platen plungers 14 of platens 10, which are held except for the lowermost platen which is obviously seen in the drawings to be held up by the ram, from moving downwardly by their respective step-supports 26, and the cakes 68 are stripped clean, being left standing exposed on the plungers 14 of platens 10 with the respective sets of springs 20 separately compressed (see Fig. 4). The cakes 68, which have been stripped by the descent of the container rings, are now free to be removed. When the press is of the vertical type, the cakes 68 are removed by simply pushing them off by hand or with any suitable implement. Shelves 70 are provided on the cake exit side. These shelves 70 protect and cover the walking pipes 46, check valve handles 56, etc., and the cakes 68 can be slid off over shelves 70 into any receptacle or conveyor (not shown) for receiving them.

As rings 12 are telescoped over plungers 14 by rods 32 to strip the cakes, any plugs of cake material extending into that part of the inlet passages 40 between the chamber 12' and the check valves 50, which check valves 50 are set back into the inlet passages 40, are automatically sheared off by plunger 14, leaving the periphery of the cake clean and free from any extending plug at the chamber inlet 40.

When the cakes have been removed, the hydraulic pressure is taken off the stripper cylinders 28. This permits the container rings 12 to be restored to original elevated position with respect to platens 10 by the action of the expanding springs 20 (see Fig. 2). The press is now ready to be supplied with a new charge, and the cycle of operation repeated, the check valve 50 being preferably initially locked momentarily, when pumping is started, in the dotted open position shown in Fig. 6 to provide for blowing the inlet passage free of any residue.

It is to be understood that the apparatus shown is for illustration only and not for limitation of my invention which is of the breadth defined in my claim.

I claim:

A press comprising a coaxial series of platens, a filter plate mounted on one face of each platen, and on the other face a plunger, a filter plate mounted on its face, container rings between the several platens and coaxial therewith, said container rings telescoping over the said plungers and forming press chambers within the said rings and between the said filter plates, means normally tending to force said rings outwardly along said plungers to expanded relation, stop means preventing said rings from being taken past telescoping relationship with said plungers, means for telescoping said rings over said plungers, means for forcing said platens toward each other to diminish the said press chambers and

5 press out liquids from solids in material to be pressed contained within the press chambers, a stationary feed manifold for supplying fluid material to be pressed, individual feed lines from the said manifold to the several container rings communicating through the ring walls with the press chambers and traveling with the rings in their axial movements, check valves in the several feed lines, a master feed control valve for all the press chambers being provided in the common manifold portion of the feed line and individual valve control means being provided for individually forcing open the several check valves to avoid the clogging of any of them.

10 15 FRED S. CARVER.
